[57] **CLAIM**

The ornamental design for a car body, as shown and described.

DESCRIPTION

FIG. 1 is a front perspective view of a car body showing my new design;

FIG. 2 is a rear perspective view thereof;

FIG. 3 is right view thereof;

FIG. 4 is left view thereof;

FIG. 5 is a top plan view thereof;

FIG. 6 is a front elevational view; and,

FIG. 7 is a rear elevational view thereof.

The wheels shown in broken lines in FIGS. 1, 2, 3, 4, 6 and 7 are for illustrative purposes only and form no part of the claimed design.
